The ornamental design for a hanger, as shown and described.

DESCRIPTION

FIG. 1 is a 3/4 front perspective view of a hanger;

FIG. 2 is a front elevational view thereof;

FIG. 3 is a rear elevational view thereof;

FIG. 4 is a left-side, elevational view thereof;

FIG. 5 is a right-side, elevational view thereof;

FIG. 6 is a top, plan-view thereof; and,

FIG. 7 is a bottom, plan view thereof.

The broken lines shown in the drawings depict unclaimed portions of the hanger that form no part of the claimed design.
